MACHINE FOR APPLYING BINDING TAPE

Jacob Wagner, Cook County, Ill.

Application December 30, 1946, Serial No. 719,324

2 Claims. (Cl. 154—1.6)

1

This invention relates to machines for applying binding tape to articles.

One use of the machine, as illustrated in the drawings, is the application of a pair of binding tapes or strips to a pair of wallet pockets or like flat article to join the same about a flexible hinge.

An object of this invention is to provide a device of the character described comprising a supporting frame, a pair of pressure rollers rotatably mounted on the frame, a platform between the rollers, rolls of binding tape from which the tape is passed over the pressure rollers with the adhesive surfaces of the tape toward each other where they pass through the space between the rollers, so that articles having portions moved over the platform and between the pressure rollers in spaced relation to one another will be attached together by the strips of tape passing around the pressure rollers and pressed against said articles as said articles move between the pressure rollers.

A further object of this invention is to provide electric motor means to rotate said pressure rollers, and switch means for said motor controlled by the article to which the tape is applied, the arrangement being such that the motor is rotated as the leading edge of the articles to be bound moves between the rollers and rotation of the motor is stopped after said articles have fully passed through the rollers.

Yet another object of this invention is to provide in a device of the character described, means to push said articles on the platform to a point where the rotation of the rollers will feed the articles and the binding tape for the binding operation.

Yet another object of this invention is to provide in a machine of the character described, adjustable means to guide said articles as they are moved between the pressure rollers.

A still further object of this invention is to provide in an article of the character described, means for adjusting the pressure of the pressure rollers relative to one another.

Yet another object of this invention is to provide in a machine of the character described, means to insure alignment of the rollers of binding tape with the pressure rollers.

Yet another object of this invention is to provide a highly improved machine of the character described so constructed that articles may be bound at greatly reduced cost, with greater speed in production and greater uniformity of product, without stitching, producing a clean binding without wrinkles or bulges and provid-

2

ing a more permanent adhesion between the binding tape and the articles bound, not subject to rip, and whereby the necessity for water dispersive glues or cements is eliminated.

5 Still a further object of this invention is to provide a highly improved device of the character described for affixing continuous adhesive coated strips to either side of a series of spaced sheets or sheetlike articles as they pass through the device.

10 Yet a further object of this invention is to provide a machine of the character described having means for feeding adhesive tape binding into contact with a series of pairs of spaced flat articles which are to be bound and including means to automatically stop the feeding operation when no articles are passing through the machine.

15 The foregoing and other objects of the invention will be more apparent from the following description when taken in connection with the drawings, in which:

Fig. 1 is a front elevational view of a machine embodying the invention;

20 Fig. 2 is a cross-sectional view taken on line 2—2 of Fig. 1;

Fig. 3 is an enlarged view of the pressure rollers platform and illustrating the control of the micro-switch above articles passing between the pressure rollers;

25 Fig. 4 is a top plan view of the machine;

Fig. 5 is a cross-sectional view taken on line 5—5 of Fig. 2;

Fig. 6 is a cross-sectional view taken on line 6—6 of Fig. 4; and

30 Fig. 7 is a partial cross-sectional view of one of the tape rolls and its support.

35 Referring now in detail to the drawings, 10 designates a machine embodying the invention. The same comprises a supporting frame structure 11. Said frame structure 11 comprises a pair of parallel side walls or plates 12 and 13. Each of said plates has a top edge 15, a rear edge 16 and a bottom edge 17. Extending upwardly from the bottom edge 17 is a front edge 18 which

40 extends about half the height of the side plate. Extending rearwardly from the upper end of edge 18 is a horizontal edge 19 from which there extends upwardly a vertical edge 20 extending to the upper edge 15. Said side walls or plates 12

45 and 13 are formed with aligned rectangular guide slots 21 located above the edges 19 and rearwardly of the edge 20, for the purpose hereinabove appearing. Said plates 12, 13 are furthermore formed with vertical openings 21a, at least partially screwthreaded, extending from the

upper edges 15 down to said slots 21 for the purpose hereinafter to be explained. The plates 12 and 13 are interconnected by a horizontal platform or wall 22 which may be fixed to the plates 12 and 13 by screws or any other suitable fastening means.

The upper surface of platform 22 is substantially at the level of the horizontal edges 19 of the side plates 12 and 13. Platform 22 extends from the front edges 18 to the rear edges 16. It is formed on its undersurface with a curved milled notch 23 which extends to the upper surfaces 22a of the platform thereby forming an opening or slot 24 in said platform. Said opening 24 is aligned with the slots 21. The slot 24 is located on the longitudinal mid-section of the platform and extends in a direction from front to rear and is located somewhat rearwardly of the vertical edges 20. On platform 22 and just forwardly of slot 24 is an upwardly projecting rib 25 parallel to the side plates 12 and 13. The forward edge 25a of said rib is curved downwardly toward the platform on its upper side for the purpose hereinafter appearing. Said platform 22 is formed in its upper surface with a pair of parallel through grooves 27 extending from front to rear in spaced relation to the plates 12 and 13.

The top edges 15 of the side plates 12 and 13 are interconnected by a horizontal bar 30. The bar 30 is parallel to the platform 22 and equally spaced from the rear ends of top edges 15. It is located rearwardly of the openings 21a for the purpose hereinafter appearing.

Fixed to the outer side of plate 12 is a horizontal motor support bracket 32, having a horizontal upper surface. There is also attached to the outside of plate 12 a pair of parallel, vertical plates 33, one located above the motor bracket 32 and one located forwardly of said motor bracket and adjacent edge 19 of said plate 12.

Mounted on bracket 32 is an electric motor 35 having an armature shaft 36 carrying a worm gear 37. The armature shaft 36 is horizontal and perpendicular to plate 12 and extends toward said plate. The plates 33 are provided with suitable bearings in which is mounted a horizontal shaft 38 perpendicular to the armature shaft 36 and located thereabove. It carries a worm wheel 39 meshing with the worm 37. On said shaft 38 is a worm 40.

Plates 12 and 13 are provided, below the platform 22, with a pair of aligned bearings or bushings 42 and supporting a horizontal shaft 43 which is located below the platform 22. Said shaft 43 is substantially in alignment with the plane of the openings 21a. Said shaft extends beyond plate 12 and carries a worm wheel 44 which meshes with the worm 40. Carried by shaft 43 is also a pinion 45.

Slidably mounted within the slots 21 are bearing blocks 50 covered by plates 51. On blocks 50 is journaled a horizontal shaft 52 parallel to and spaced above the shaft 43. Shaft 52 passes beyond the bearing block in plate 12 and carries a pinion 53 similar to and meshing with the pinion 45. It will now be understood that when the motor is rotating, shafts 43, 52 will be rotated in opposite directions at equal rates of speed.

Looking at Fig. 2, shaft 43 rotates in a clockwise direction whereas shaft 52 rotates in a counterclockwise direction. On the center of shaft 43 is an externally corrugated pressure roller 55 which may be fixed in adjusted position on the shaft by means of suitable set screws. The pres-

sure roller 55 projects into grooves 23 and passes into slot 24. Mounted on the shaft 52 is a pressure roller 56 similar to pressure roller 55 and in alignment therewith.

Engaged within the threaded openings 21a are vertical elongated screws 57 contacting the bearing blocks 50 for pressing the top pressure roller 56 toward a bottom pressure roller 55. On the screws 57 are lock nuts 57a to retain the screws 57 in adjusted positions.

Fixed to plate 13, in any suitable manner, are a pair of horizontal shafts 60. The shafts 60 are in the same vertical plane located rearwardly of the shafts 43, 52. On each shaft 60 are a pair of adjusting collars 61. Between said collars are annular plates 62 and 63. Plate 62 is formed with an externally threaded sleeve 62a engaging the internal threads of a sleeve 63a extending from flange 63. Flanges 62, 63 form a holder for a roll 64 of binding tape. The position of the binding tape on shaft 60 may be adjusted by means of the adjusting collars 61. Said collars may be provided with set screws 65 so that they may be adjustably fixed to the shaft 60 in desired position. The rolls 64 of tape may be adjusted into alignment with the pressure rollers 55, 56. There is thus provided top and bottom pressure rollers 56 and 55 and top and bottom rolls of tape. The tape 64a from the top roll 64 may be passed over the roller 56 with the adhesive side of the tape away from the roller. The adhesive strip of tape from the bottom roll 64 may be passed over the roller 55 likewise with the adhesive side of the tape away from the roller.

Means is provided to move articles to be bound by the strips of tape 64a, along the platform. To this end there is slidably mounted in the grooves 27, bars 27a interconnected by a transverse horizontal bar 70 which rides on top of the platform 22. At the center of the leading edge of the bar 70 is a guide lug 71 aligned with the rib 25. Thus an article placed on the platform and in front of the movable guide bar 70 may be moved toward the pressure rollers by moving the guide bar from front to rear. For the purpose of illustration, the machine is illustrated in the drawing as applying the binding strips 64a to opposite sides of a pair of wallet pockets 75 for attaching the pockets together. The pockets 75 may be made of transparent plastic sheeting. Their open ends are at 76 and their closed ends are at 77. A pair of right and left wallet pockets are placed on the platform in front of the bar 70 with the inner or closed edges 77 contacting the lug 71 and rib or ridge 25.

Means is provided to guide the outer edges 76 of the articles to be bound together. To this end there is mounted on the platform a pair of flat adjustable guide plates 78. Each of the guide plates 78 is formed with a pair of parallel transverse slots 79. Fixed to the platform 22 and extending upwardly therefrom are screws 80 and on said screws are nuts 80a. The screws pass through the openings 79 and the nuts are adapted to contact the upper surface of the plate 78. When the nuts are loosened the plates 78 may be adjusted inwardly to almost contact the edges 76. The nuts may then be tightened to fix the plate 78 in adjusted position. It will be noted that the plates 78 overlie the bar 27a and thus serve to keep said bars within the grooves 27. Although wallet pockets are shown for the purpose of illustration as being bound by the strips 62a, it will be obvious that any other flat articles or

sheets may be bound or attached together by the machine described herein.

The articles 75 are placed on the platform in spaced symmetrical relation as shown in Fig. 5. When the bar 70 is moved forwardly, said articles will enter between the rollers and the adhesive surfaces of the tape strip will be pressed against said articles so that as the pressure rollers rotate, the binding strips will be pressed against opposite sides of said articles to attach them together. Obviously, the center portions of the strips will contact one another and adhere together. Once the articles are gripped by the rollers it is not necessary to push the articles 75 any further by means of bar 70 as the rollers thus will advance the articles through together with the strips of tape.

Means is provided to energize the motor when an article to be taped is moved toward the pressure rollers and to stop rotation of the roller when the articles have passed beyond the rollers. To this end there is fixed to bar 30 a downwardly extending vertical plate 81. Plate 81 is disposed between shafts 52 and 60 and terminates above platform 22. Fixed thereto and extending forwardly thereof is a microswitch 82 which includes a switch arm or lever 83 projecting forwardly of a point in front of and at one side of the opening 24. The switch 82 is so connected to the motor that when arm or lever 83 is pressed upwardly, the motor is energized, and when arm 83 is released the motor circuit is broken and the motor is de-energized. When the articles to be taped approach the rollers, the leading edge of one of the articles will engage the arm or lever 83 and close the micro-switch to complete the motor circuit to energize the motor. The pressure rollers 55 and 56 are then rotated for feeding the article between the rollers and causing the articles to be bound together. When the articles pass beyond the leading or hooked end of the switch arm or lever 83, said switch arm is released and opens the motor circuit to stop the rotation of the motor. Obviously the binding may be applied to a single article instead of two articles for the purpose of joining them together, or a single binding roll may be employed.

The operation of the device will now be described.

The rolls of binding tape are placed on the two center threaded interlocking plates 62, 63. Care should be taken so that the impregnated side of the binding strip does not touch the pressure roller but appears at the outside of the pressure roller. The same caution should be taken when installing the bottom binding roll. The binding rolls should be located in alignment with the pressure rollers and tightened in position by means of the collars 61. Then draw the binding strip from the top and bottom rolls and place them over the pressure rollers as close to the junction of both rollers as possible. Then lift the switch lever 83 gently allowing the bindings to be drawn into and between the pressure rollers. Since the pressure rollers are operating at the same speeds, the top binding and the bottom binding will emerge fused. Slight adjustment may be necessary to line up the bindings.

Then push the slide bar until its outer edge is in alignment with the leading edge of the platform 22. Then place the wallet pocket or other articles to be bound on the platform flush with the rear edge of the horizontal bar 70. Then move the right pocket to the left until it contacts lug 71. Repeat the same for the left

sheets may be bound or attached together by the machine described herein. Then place the right hand on the right pocket and the left hand on the left pocket. Four fingers are to rest lightly on the article 75 while the thumbs rest on the horizontal bar 70. Then move the horizontal bar 70 rearwardly. The horizontal bar will move the pockets rearwardly until said pockets overlap the guide plates 78. Make sure not to move the switch lever during this operation. Then move in the side guides 78 until they barely touch the articles 75. Then tighten the guides 78. Replace the hands as previously described and move the bar 70 forwardly until bar 70 contacts plate 78. As the articles pass under the pressure sensitive switch 83, the motor will rotate the rollers which start drawing the bottom and top binding and article 75 rearwardly. The bottom binding becomes affixed to the bottom of the two articles, while the top binding becomes affixed to the top of said articles. As soon as the articles pass the switch, the motor will stop. Then draw the slide bar to its original position and repeat. Two articles are thus joined together into a single product by two pieces of binding. Obviously the binding between the pairs of bound-together articles may later be severed.

It will be readily seen that my invention is capable of modification of the embodiment herein described and I therefore do not wish to be strictly confined to the structure set forth.

The scope of the invention is defined in the accompanying claims.

What is claimed is:

1. In combination, a pair of parallel side walls, a horizontal platform supported by and between said side walls, a horizontal shaft rotatably mounted on said side walls and beneath said platform, a pair of bearing blocks slidably mounted on said side walls, a horizontal shaft journalled in said bearing blocks, said platform having an opening, similar aligned pressure rollers on said shafts, the roller on the first shaft projecting through said opening, means to rotate said rollers in opposite directions at the same rate of speed, horizontal shafts on at least one of said side walls, one above and one below said platform, means on said last shafts to support rolls of binding tape, the tape from the top roll being adapted to be passed onto the top roller, and the tape from the bottom roll being adapted to be passed over the bottom roller, said means for rotating the roller shafts comprising an electric motor, a switch controlling said motor located above the platform and adjacent said rollers so that an article moved on the platform will contact said switch, and a bar on said platform parallel to said shafts and slidably mounted on said platform for movement in a direction perpendicular to said bar.

2. In combination, a pair of parallel side walls, a horizontal platform supported by and between said side walls, a horizontal shaft rotatably mounted on said side walls and beneath said platform, a pair of bearing blocks slidably mounted on said side walls, a horizontal shaft journalled in said bearing blocks, said platform having an opening, similar aligned pressure rollers on said shafts, the roller on the first shaft projecting through said opening, means to rotate said rollers in opposite directions at the same rate of speed, horizontal shafts on at least one of said side walls, one above and one below said platform,

means on said last shafts to support rolls of binding tape, the tape from the top roll being adapted to be passed onto the top roller, and the tape from the bottom roll being adapted to be passed over the bottom roller, said means for rotating the roller shafts comprising an electric motor, a switch controlling said motor located above the platform and adjacent said rollers so that an article moved on the platform will contact said switch, and a bar on said platform parallel to said shafts and slidably mounted on said platform for movement in a direction perpendicular to said bar, and guide members on said platform to guide articles on said plat-

5
form as they are moved by said bar upon slidably moving said bar on said platform.

JACOB WAGNER.
